Fig. 3

FIGURE 1 is a front view of a condition responsive device embodying the new design;

FIGURE 2 is a top view of the device;

FIGURE 3 is a side view as seen from the right side of the device, the left side being substantially a mirror image thereof; and

FIGURE 4 is a fragmentary cross-sectional view taken generally along line 4—4 of FIGURE 1.

The back and bottom of the device are essentially plain.

The dominant features of the design reside in the portions shown in full lines.

I claim:

The ornamental design for a condition responsive device, substantially as shown and described.
